(57) **CLAIM**

The ornamental design for a valance clip, as shown and described.

DESCRIPTION

FIG. 1 is a front perspective view of the valence clip showing my new design;

FIG. 2 is an enlarged right side view thereof, shown with a valence installed;

FIG. 3 is a perspective view, shown with a secondary clip and a valence installed; and,

FIG. 4 is another perspective view, shown with a secondary clip and an alternate valence installed.

The broken lines are for illustrative purposes only and form no part of the claimed design.
